SNAP RING SOCKET

Daniel I. Reiter, New York, N. Y.

Application April 17, 1941, Serial No. 388,962

19 Claims. (CL 24—218)

This invention relates to snap fastener sockets and particularly to the type provided with a resilient wire ring and which is secured to one face of a sheet of material by a cap arranged on the other face of the sheet.

With the more extensive use of snap fasteners in washable garments and at places in garments designed to sustain considerable tension, as in waist bands where considerable side pull is applied to the separable snap fastener parts tending to separate them, former types of snap fasteners have proved to be inadequate to hold the fastener parts together under the comparatively high stresses present and to withstand the effects of laundering and pressing the garment. The comparatively high pressures necessary when the garment is pressed, frequently distorts the snap fastener socket to such an extent as to render it useless for its intended purpose. Furthermore, high tension on the respective parts to which the stud and socket of the fastener are attached tends to open the fastener or to distort the socket so that it does not properly engage and hold the stud in place.

My invention therefore contemplates the provision of a snap fastener socket having a resilient stud-engaging wire ring and ring-holding parts so shaped, constructed and mutually reinforced as to enable the fastener to withstand the stresses to which the socket is subjected when in use and the additional distorting stresses put on the socket when the garment to which it is applied is laundered or pressed.

My invention further contemplates the provision of a socket having a bracing and protecting member which protects the resilient ring of the socket against distortion, and, which also adequately holds the ring in place while having the additional function of cooperating with the ring-holding parts of the socket to resist the stresses to which the garment is subjected in the course of wear, laundering or pressing.

My invention further contemplates the provision of a socket having a protected stud-engaging ring designed to fit the stud closely and thereby to attain a strong holding action.

The various objects of the invention will be clear from the description which follows and from the drawing, in which,

Fig. 1 is a partial vertical section and partial elevation of my improved socket as it appears when applied to a sheet of material forming part of a garment, and showing the cooperating stud secured to another part of the garment,

and engaged by a socket ring of elliptical cross-section.

Fig. 2 is a similar view of a modified form of the invention wherein a ring of circular cross-section is shown.

Fig. 3 is a similar fragmentary view of another modified form of the invention, the ring shown being of oval cross-section.

Fig. 4 is a similar view of still another modified form of the invention, wherein the holding prongs are provided on the ring-holding element and are forced into the socket cap.

Fig. 5 is a bottom plan view of the same partly broken away to show the interior.

Fig. 6 is a vertical section of the pronged ring-holding part of the socket shown in Figs. 4 and 5.

Fig. 7 is a similar fragmentary section of a modified form of the ring-holding parts.

Fig. 8 is a similar section of another modified form of the socket.

In the practical embodiment of the invention which I have shown by way of example, and referring particularly to Fig. 1, the socket is secured to a portion 10 of a garment by means of a suitable cap 11 here shown as provided with bendable fingers which pass through the garment part and hold the inner socket part in place. The stud-engaging ring 13 is preferably of the circular open end or split type, that is, with its ends in slight spaced relation to permit its expansion and contraction under the pressure of a stud forced into the socket or withdrawn therefrom. Said ring is preferably made of a length of wire bent into circular form and arranged loosely in the socket to permit its free expansion and contraction. As shown, the wire is of elliptical cross-section to fit a corresponding recess in the stud and to obtain a more greatly accentuated snap and holding action.

The cap 11, in the form now being described, comprises an outer annular or flat ring portion 14 designed to engage one face of the garment part 10, and a series of separated fingers 15 designed to pierce the garment and to be bent outwardly and upwardly to secure the socket against the other face of the garment when the cap and ring-holding part are pressed axially toward each other. When so pressed, the fingers 15 enter the space 17 between the curved outermost wall 18 and the wall 19 of the inner ring-holding member 20, the fingers being spread and bent by said member, following the curve of the wall 18.

Preferably the wall 19 projects inwardly and

upwardly from the inner edge of the wall 18 and is arranged coaxially thereof though shaped differently therefrom. Depending integrally from the inner end of the wall 19, is the innermost wall 21 of the member 20, said wall terminating at its lower edge in an upright or cylindrical portion 22 arranged outwardly beyond the ring 13 and of somewhat greater height than that of the ring. The upper part of the wall 21 inwardly overhangs the ring 13 to a line above the circular axis of the ring. It will be understood that the wall 21 is properly shaped to provide sufficient space for the reception of the head of the stud in the socket, the constricted neck of the stud receiving the ring 13, which separably holds the stud against accidental displacement or separation from the socket until the parts are deliberately separated by relative axial movement thereof. It will also be noted that an intermediate part of the wall 21 is in contact with an adjacent part of the wall 19, whereby any outward pressure upon the said wall 21 is resisted by the wall 19 and by the bent portions of the fingers 15, so that said walls are mutually bracing.

The substantially cylindrical wall part 22 is by itself inadequate to hold the ring 13 in place except against upward and outward movement. Consequently, the outer or cover member 23, having the central stud-receiving opening 24, is provided to complete the socket, to protect the ring 13 and the walls 21 and 18, and to strengthen and reinforce the socket against the stresses which result from laundering and pressing and also from stresses put upon the socket during the use thereof. Said member 23 is of substantially U-shaped cross-section, having an upstanding rim or peripheral outer portion curved about the wall 18 to a sufficient extent to hold it securely in place. The inner or central portion 25 of said member is flat and engages the lowermost edge of the wall 21 and projects inwardly therewith to a point below the circular axis of the ring 13. Said inner portion 25 therefore serves as an adequate protector to prevent distortion of the wall 21 and particularly of the lower part 22 thereof and also serves to confine the ring 13 in place. Preferably, the part 25 is horizontal or substantially perpendicular to the axis of the socket. The pressure of a pressing or ironing member on the part 25 does not bend said part because of the support given thereto by the portion 22 of the ring-holding member. Similarly, the ring-holding member is not distorted because of the reinforcement of the wall 21 by the wall 19, the fingers 15 and the outer part of the member 23.

It will be noted that because of the peculiar cross-sectional shape of the ring 13, it resists expansion to a greater extent than would a ring of circular cross-section. It will further be noted that the ring 13 enters into the constricted neck recess or groove in the stud to a greater extent than would a ring of round wire. Consequently, the holding action on the stud is increased as is the resistance to separation of the stud from the socket. Side pull on the stud or socket cannot separate them, not only because of the better holding action of a ring of non-circular cross-section, but also because the parts cannot be distorted to permit undue distortion of the ring and loss of holding power. It will be understood, however, that rings of any desired cross-section may also be used in the various sockets shown in place of the rings of round wire illustrated, provided that the cross-section is sufficiently wide,

as measured in the plane of the ring, to permit a substantial amount of the ring to enter the neck constriction or groove of the stud. It will further be noted that two thicknesses of material are provided at all points of the socket which are subjected to substantial stress or distorting forces, particularly at the socket rim and the ring-holding inner walls, and that selected parts of the walls of the socket members are in contact to give the desired bracing effect.

In the form of the invention shown in Fig. 2, I have shown my improved socket adapted for use with an eyelet form of holding member or cap. This requires a change in the form of the inner ring-holding member. I have also shown the resilient ring 30 made of wire of circular cross-section. The outer ring-holding member 31 is provided with an inner flat part 25a similar to the part 25 of the socket shown in Fig. 1 hereinbefore described, and serving substantially the same purpose. The outer rim part 32 of said member 31 is shaped to fit and engage the curved part 33 of the inner ring-holding member, said inner member having a wall 19a similar to the wall 19 shown in Fig. 1 and a wall 21a similar to the wall 21 shown in the socket of Fig. 1. The lower part 22a of the wall 21a is substantially cylindrical and straight and is covered by the inner part 25a of the member 31 and braced thereby, the part 25a extending inwardly past the part 22a, all as has been previously explained in connection with the socket shown in Fig. 1. However, in place of the wall 18, there is provided in this form of the invention, an upright wall portion 34, closed by a substantially horizontal top 35 arranged at substantially right angles to the wall part 34 and provided with a central opening 36 for the passage therethrough of the eyelet 37. Said eyelet clamps the cap 38 in place to one face of the sheet 10 and passes through the sheet and through the opening 36 in the top wall 35, to be flanged into a suitable recess in said top wall surrounding the opening 36.

In the form of the invention shown in Fig. 3, the ring-holding parts are made similar to those shown in Fig. 1, but the ring 40 is shown as made of wire of oval cross-section and the cap 39 is provided with a closing portion connecting the outer peripheral edges of the flange 14a, which is substantially identical with the flange 14 shown in Fig. 1.

In the form of the invention shown in Figs. 4, 5, and 6, the outer member 23b of the socket is provided with a curved outer rim or outstanding peripheral portion bent around the correspondingly curved portion 45 of the cooperating ring-holding member, the portion 46 extending inwardly and upwardly as a conical wall holding the ring 47 in place against upward and outward movement, while the inner part 25b of the other ring-holding member 23b serves to hold the ring against downward displacement. Extending upwardly from the outer edge of the wall part 45 are the spaced prongs 48 passing through the sheet 10 and into engagement with the wall 49 of the cap member 50, to be bent thereby when the cap member and the socket are forced toward each other, thereby to hold the socket to the sheet. Consequently, only one inner wall is provided in this form, though the double thicknesses of material are provided elsewhere where needed.

In Fig. 7 showing a slightly modified form of the inner ring-holding member disclosed in Figs. 4, 5 and 6, the wall 46a is bent inwardly to con-

form more nearly to the shape of the ring 47, instead of being made conical as is shown in Figs. 4 and 6.

In the form of the socket shown in Fig. 8, part of the outermost wall 18 shown in Fig. 1 is omitted, and the ring is shown as of circular cross-section, but the socket is otherwise substantially the same as that shown in Fig. 1. The cap 11 is provided with the fingers 15 as previously described, but the inner socket member 55 terminates at an outer edge 56 adjacent the flat portion 57 of the outer ring-holding member 58. Said inner socket member includes the contacting and mutually bracing walls 19b and 21b similar to the walls 19 and 21 previously described, which walls are joined by the bend 59. The member 58 is continued outwardly substantially past the edge 56 of the wall 19b to a height about equal to the height of the walls 19b and 21b, thereby to present a smooth outer surface on the socket instead of the two parts shown in the modifications hereinbefore described. The wall 21b is nevertheless adequately protected and braced and the ring 30b is also protected against permanent deformation.

It will be seen that I have provided a ring-holding socket wherein the ring-holding parts are in engagement with each other and bent in such a manner that the edges thereof are protected against undue distortion such as might cause distortion of the ring and failure thereof to hold the stud under the various stresses put upon the socket, and that two mutually bracing thicknesses of material are provided where the stresses upon the socket are greatest.

While I have shown and described certain specific embodiments of my invention, I do not wish to be understood as limiting myself thereto, but intend to claim the invention as broadly as may be permitted by the state of the prior art and the scope of the appended claims.

I claim:

1. In a resilient snap fastener socket, a resilient ring, and a pair of cooperating annular and coaxially arranged ring-holding members, the inner of said members having an inner wall terminating in a lowermost edge part of greater diameter than that of the upper part of said wall, said inner member having an outer annular wall, the outer of said members having a curved outer peripheral part retaining the outer wall of the inner member in place, the outer member having an inner flat part substantially perpendicular to the axes of said members and extending inwardly past the lowermost edge part of the inner member and in contact therewith, the ring being arranged above said flat part and between the flat part and the upper part of the inner wall of the inner member, said walls being in radial spaced relation and of different cross-sectional shapes, the outer wall of the inner member being in contact with the outer member at least at the outer peripheral portion of said flat part to form two thicknesses of material at said peripheral portion.

2. In a resilient snap fastener socket, a resilient open-ended wire ring, a pair of cooperating annular and coaxially arranged members having their outer peripheral parts in contact to provide two thicknesses of material, said members cooperating to hold the ring in position for the expansion and contraction thereof under the pressure of a cooperating stud, each of the members having a central stud-receiving opening 75

therein and being otherwise continuous and imperforate, the inner of the members having at least two co-axially arranged and differently shaped walls at least in part in spaced relation and joined at adjacent edges thereof by a continuous annular bend subtending an angle of approximately 180° to form a reverse fold, the inner of the walls terminating in a free edge opposite the bend and being shaped to provide a lowermost part of greater diameter arranged entirely outwardly of the ring, and an uppermost part of lesser diameter inwardly overhanging the ring, the other of the members being of substantially U-shaped cross-section having a central flat part extending past and in contact with the adjacent part of the inner wall of the inner member and directly below the ring.

3. In a resilient socket, an open ended ring of wire having a non-circular cross-section, the width of the wire in the general plane of the ring being greater than its height, and means for holding the ring in place comprising a pair of cooperating annular members, one of said members being of generally U-shaped cross-section provided with a flat part surrounding a central opening therein and with an upstanding outer rim, the inner peripheral part of said one member adjacent the opening being arranged directly below the ring to retain the ring within the socket, and the other of said members having a plurality of co-axial but differently shaped walls, the innermost of said walls having an upper part inwardly overhanging the ring to the same extent as the flat part of said one member, said inner wall having a lower part arranged outwardly of the ring and inwardly of the outer peripheral edge of the flat part of said one member.

4. In a resilient socket, a resilient ring, and a pair of cooperating annular bent sheet metal members to retain the ring in place, said members having central stud-receiving openings therein for the passage of a stud into engagement with the ring, the outer of said members being of generally U-shaped cross-section having an upstanding curved rim and a substantially horizontal flat central part, the innermost peripheral edge portion of said flat part engaging the outer part of the ring, the other of said members having three co-axial walls, each of the walls being shaped differently from the other walls, the outermost wall being curved into engagement with the upstanding rim of said one member and being spaced from the adjacent wall sufficiently to receive the bendable fingers of a holding cap, said next adjacent wall being joined to the innermost wall by an integral bend at the adjacent uppermost edges thereof, the innermost wall having the upper part thereof overhanging the outer part of the ring and having a cylindrical lowermost part arranged entirely outwardly of the ring and terminating in a free edge in contact with the flat part of said one member.

5. In a resilient socket, a resilient ring, and a pair of ring-holding members, the outer parts of said members being in contact to form two thicknesses of material at the outer periphery of the socket, the inner part of one of the members being arranged below the ring and being substantially flat and the inner part of the other member comprising a pair of co-axial walls, the innermost of the walls terminating in a cylindrical part arranged outside of the ring and

having a free edge in contact with the inner flat part of said one member, the upper part of said innermost wall inwardly overhanging the ring.

6. A snap fastener socket installation comprising a resilient ring, a pair of cooperating and mutually bracing annular ring-holding members, one of said members being of substantially U-shaped cross-section having an upstanding rim portion and a central flat portion extending inwardly past the outer part of the ring underneath the ring, the other member having a conical inner wall adapted to limit the upward and outward movement of the ring and arranged inside of said one member, said other member having an outer wall curved to engage the inner face of said rim, and having upstanding spaced prongs, and a cap member provided with an anvil wall adapted to bend said prongs outwardly when the cap and the members are pressed toward each other with a sheet of fabric therebetween.

7. In a resilient snap fastener socket installation, a resilient ring, a pair of cooperating and mutually bracing annular ring-holding members, one of said members being of substantially U-shaped cross-section having an upstanding rim portion and a central flat portion extending inwardly past the outer part of the ring underneath the ring, the other member having an innermost wall terminating in a free edge portion arranged outwardly of the ring and an upper portion inwardly overhanging the ring, a second wall joined by a bend to said upper portion, and arranged outwardly thereof, a third outer wall curved to fit the rim and having a recessed top provided with a central eyelet opening, a cap and an eyelet engaging the cap passing through the eyelet opening and through a sheet of fabric and flanged to the under side of said top.

8. In a resilient socket, a resilient ring and a pair of separate annular ring-holding members overlapping in part on each other, the remaining part of said members being in spaced relation to each other, the outer parts of said members being in contact to form two thicknesses of material adjacent the outer periphery of the socket, the inner part of one of the members being arranged below the ring, and the inner part of the other member comprising a wall arranged coaxially of and in spaced relation to

the outer part of said one of the members and of a different cross-sectional shape than the cross-sectional shape of the outer part of said one of the members, said wall terminating in a part arranged outside of the ring and having a free edge in contact with the inner part of said one member, the uppermost part of said wall inwardly overhanging the ring.

9. In a resilient socket, a resilient ring, and means for holding the ring in place comprising a pair of cooperating annular members, one of said members being of generally U-shaped cross-section provided with a central part surrounding a central opening and with an upstanding outer rim, the inner peripheral part of said one member adjacent the opening being arranged directly below the ring to retain the ring within the socket and the other of said members having a plurality of coaxial, but differently shaped walls, the outermost of said walls being in outward spaced relation to the adjacent inner wall, said outermost wall and said inner wall having the lowermost parts thereof arranged at substantially the same level, the innermost of said walls having an upper part inwardly overhanging the ring to the same extent as the central part of said one member, said innermost wall having a lower part arranged outwardly of the ring and inwardly of the outer peripheral edge of the central part of said one member.

10. In a resilient socket, a resilient ring, and means for holding the ring in place comprising a pair of cooperating annular members, one of said members being of generally U-shaped cross-section provided with a central opening and with an upstanding outer rim, the inner peripheral part of said one member adjacent the opening being arranged directly below the ring to retain the ring within the socket, and the other of said members having a plurality of coaxially arranged, but differently shaped walls, the innermost of said walls being in inward spaced relation to the outermost of said walls and having an upper part inwardly overhanging the ring to the same extent as that part of said one of the members surrounding the opening, said innermost wall having a part arranged outwardly of the ring and outwardly of the edge of said one opening.

DANIEL I. REITER.
